DESIGN FOR A BACON PRESS OR SIMILAR ARTICLE

Marshall D. Gibson, Webster Groves, Mo.

Application December 8, 1944, Serial No. 116,798

Term of patent 14 years

(Cl. D44—29)

To all whom it may concern:

Be it known that I, Marshall D. Gibson, a citizen of the United States, residing at the city of Webster Groves, county of St. Louis, State of Missouri, have invented a new, original, and ornamental Design for a Bacon Press or Similar Article, of which the following is a specification, reference being had to the accompanying drawing forming part thereof.

Fig. 1 is a top plan view of a bacon press showing my new design; and

Fig. 2 is an edge elevational view thereof.

I claim:

The ornamental design for a bacon press or similar article, as shown.

MARSHALL D. GIBSON.
